UNITED STATES PATENT OFFICE.

HERBERT S. PULLMAN, OF MERIDEN, CONNECTICUT.

DESIGN FOR AN EGG-SEPARATOR.

SPECIFICATION forming part of Design No. 29,139, dated August 2, 1898.

Application filed June 8, 1898. Serial No. 682,950. Term of patent 7 years.

To all whom it may concern:

Be it known that I, HERBERT S. PULLMAN, of Meriden, in the county of New Haven and State of Connecticut, have invented a new 5 Design for an Egg-Separator; and I do hereby declare the following, when taken in connection with the accompanying drawings and the letters of reference marked thereon, to be a full, clear, and exact description of the 10 same, and which said drawings constitute part of the specification, and represent, in—

Figure 1, a plan view of my newly-designed utensil; Fig. 2, a sectional view thereof on the line *a b* of Fig. 1; Fig. 3, a corresponding view on the line *c d* of Fig. 2.

15 My invention relates to a design for an egg-separator; and the design consists in the configuration of the utensil, as herein shown and described.

As herein shown, the design consists in a 20 hemispherical cup A, pierced by six radially-arranged long slots B, having rounded inner and outer ends and equidistant from each other. The edges of the slots are slightly turned outward, so as to appear in the form 25 of long radially-arranged fins C upon the outer surface of the utensil.

I claim—

The design for an egg-separator as herein 30 shown and described.

In testimony whereof I have signed this specification in the presence of two subscribing witnesses.

HERBERT S. PULLMAN.
